UNITED STATES PATENT OFFICE.

CHARLES H. CRUMP, OF BOSTON, MASSACHUSETTS.

DESIGN FOR BOLSTERS FOR KNIVES OR FORKS.

Specification forming part of Design No. 6,649, dated May 13, 1873; application filed May 7, 1873.

To all whom it may concern:

Be it known that I, CHARLES H. CRUMP, of Boston, of the county of Suffolk and State of Massachusetts, have invented or produced a new, useful, and original design, shape, or configuration of a Table Knife or Fork Bolster, and do hereby declare the same to be fully described in the following specification and represented in the accompanying drawing, of which—

Figure 1 is a side view, Fig. 2 an end view, and Fig. 3 a horizontal section, of a bolster of my new pattern, configuration, or design, parts of the blade A and handle B of a table-knife, being shown with the bolster.

In the design in question, the opposite bearing facets *a a* of the bolster C are rectangular planes, whose lower edges are straight or slightly convex. The back and front, in continuation of the said facets *a a*, are curved, as shown at *b c*. From such surfaces the bolster

tapers down pyramidal to, or about to, a rectangular base with rounded corners, that part of the bolster which is below the bearing-facets, or between them and the handle B, being an approximation to an inverted pyramidal frustum, the part directly above being an approximation to a quadrilateral prism.

From the top of each of the facets the bolster curves up to the blade in manner as shown at *d*.

This shape or configuration of bolster, besides being ornamental, is a useful one, as it admits of being readily cleaned.

I claim as my invention—

The knife or fork bolster design, shape, or configuration, substantially as specified.

CHARLES H. CRUMP.
